UNITED STATES PATENT OFFICE.

LAZARD KAHN, OF HAMILTON, OHIO, ASSIGNOR TO F. & L. KAHN & BROTHER,
OF SAME PLACE.

DESIGN FOR A STOVE.

SPECIFICATION forming part of Design No. 21,024, dated September 1, 1891.

Application filed July 17, 1891. Serial No. 399,890. Term of patent 7 years.

To all whom it may concern:

Be it known that I, LAZARD KAHN, of Hamilton, Butler county, Ohio, have invented a certain new and original Design for a Stove, 5 of which the following is a specification, reference being had to the accompanying drawing, which is a perspective view of a stove embodying my new design.

My design may be described as follows:

10 Referring to the drawing, the body A is cylindrical, and is surmounted by a top B, with its rim projecting beyond the body, the top extending upward to form what might be termed a "flattened cone" of curved contour, 15 with an inward reduction in diameter at C. At the base of the cylindrical body is a hori-

zontal non-circular flange E, below which the circular fire-pot D forms a downward continuation of the body, the fire-pot tapering downwardly and resting upon the circular 20 skirt-ring F, having a segmental contour. Legs H join the base of the skirt. A rectangular ash-pit door presents itself at the foot of the skirting, partly above and partly below the base-line of the skirting. 25

I claim—

A design for a stove, as herein described and shown.

LAZARD KAHN.
